PRESS BUTTON TUNED RADIO RECEIVER

Willi Patzschke, Berlin-Zehlendorf, and Erwin König, Berlin-Wilmersdorf, Germany, assignors to General Electric Company, a corporation of New York

Application September 7, 1940, Serial No. 355,722
In Germany July 27, 1939

1 Claim. (Cl. 171—242)

The invention is concerned with a press button tuned radio or signaling apparatus comprising tuning coils which are capable of being cut in circuit or disconnected by the actuation of the press buttons. Now, according to the invention such apparatus are provided with an arrangement which in a simple manner insures tuning of the coils to different transmitters. For the purpose of tuning the coils, rotary knobs are provided preferably below the press button molding strip.

An exemplified embodiment according to the invention is shown in the appended drawing. Fig. 1 shows in schematic form an arrangement according to the invention as applied to a radio broadcast receiver apparatus. Fig. 2 illustrates a detailed view of an arrangement according to the invention, while Fig. 3 shows a top view of part thereof.

Referring to Fig. 1, 22 represents the push buttons. By pushing one of the press buttons the coils corresponding thereto are cut in circuit, with the result that the apparatus picks up the transmitter to which the said coil is tuned. Below the press buttons 22 and placed slightly towards the rear are the rotary knobs 15 which allow the tuning coils to be tuned to any desired transmitter. Above the press buttons 22 and slightly recessed in the casing 24 is the scale 23.

Referring to Fig. 2, 1 and 2 denote the tuning coils, two thereof being tuned simultaneously each time. For instance, coil 1 belongs to the input circuit, while coil 2 belongs to the local oscillator. Coil 1 is tuned by means of the dust-core 3, while coil 2 is tuned by the dust-core 4. The said two dust-cores 3 and 4 are supported by a shaft 5 provided with a screw-thread. A non-magnetic spring 6 is clamped between the cores 3 and 4, the said spring pressing the cores 3 and 4 against the lock nuts 7 and 8. The shaft 5 is journaled in the two end plates 9 and 10 of a tubular piece or sleeve 11, each of the end plates being provided with a female screw-thread, so that when the shaft 5 is turned it is shifted in axial direction together with the dust cores 3 and 4. Tube or sleeve 11 serves at the same time as the support for the tuning coils 1 and 2 and is attached to a part 12 which is connected to the chassis of the apparatus. Shaft 5 passes through a bore-hole provided in part 12 and has arranged at its end a fixedly connected driving means 13. The latter comprises two arms or tappets by which it is driven by the rotor 14 upon the latter being rotated.

Rotor 14 has at its outer end a rotary knob 15 by means of which adjustment of the tuning coils is insured. Rotor 14 is journaled in a bore-hole 16a of the front panel 16. A spiral spring 17 is clamped between the collar 18 of the rotor 14 and a washer disc 19 which presses against the inner surface of an enclosure member or mold piece 20. The said spring 17 presses the rotor 14 against the molding 12 attached to the chassis of the apparatus. The end of the rotor near the coils is provided with slots. Through the slots 21 project the arms of the driving means 13 so that upon rotation of the rotor 14 they are driven, while being capable of axial shift with respect to the rotor.

To the end of insuring simple mounting, the washer disc 19 is made elasical, while the inside diameter of the same is made equal to, or smaller than, the diameter of the rotary knob 15 so that the washer disc 19 has only to be shifted over the rotary knob 15 during assembly. Such an arrangement is multiple in nature, indeed in the arrangement shown in Fig. 1 it is six-fold corresponding to the number of press buttons provided.

Now, the device operates as follows: By means of nut 7 or nut 8 the distance between the cores 3 and 4, for instance, by slots provided in the tube or sleeve 11, is so adjusted that the coils 1 and 2 have the same inductance for each setting of the rotary knob 15. Once this condition has been attained then it is possible at any instant to adjust the various tuning coils by rotation of the rotary knobs 15 so as to be tuned to any desired transmitter without the casing of the radio receiver apparatus having to be opened.

An arrangement according to the invention may be subsequently mounted in an apparatus if the shaft 5 were covered, for instance, by means of a protecting lid or cover, and after removal of the latter, was set, for instance, by means of a screw driver.

By an arrangement according to the invention the rotor 14 is tensionally pressed in axial direction against the chassis of the apparatus so that rattling of the rotor 14 when being adjusted is precluded.

When mounting the chassis of the apparatus in the casing, it is generally impossible to avoid poor fit between the molding 20 and the front panel 16. However, by means of the spring 17 rotor 14 is always held in tensional connection with molding 20 so that axial play of the rotary knob 15 is obviated.

We claim:

In a tuning assembly, a main panel and a sub-panel arranged in spaced parallel relation and provided with coaxial openings, an axially adjustable shaft mounted substantially normal to said panel and having one end thereof protruding through the sub-panel opening, a plurality of cores slidably and coaxially mounted on said shaft, resilient means acting upon said cores and tending to force the cores apart in an axial direction, adjustable stops mounted on said shaft and cooperating with said cores for limiting the axial displacement of the cores relative to each other and the shaft, an up-turned element fixedly mounted on the shaft end which protrudes through the sub-panel, and an operating means for said shaft located between said two panels

and having a portion mounted within the opening of the main panel and provided with a key-way into which said up-turned element is fitted, said operating means having a portion which protrudes an appreciable distance beyond the outer face of said main panel, an enclosure member mounted on the outer face of said main panel for covering the opening therein, said enclosure member being provided with an opening through which the protruding portion of the operating means extends, and resilient means interposed between the panel side of the member and the operating means for holding the latter means tightly against the sub-panel.
